INVENTOR:—
William E. Stubbs,
BY Joshua Pusey,
ATTORNEY.

UNITED STATES PATENT OFFICE.

WILLIAM E. STUBBS, OF CHESTER, PENNSYLVANIA.

PUZZLE DEVICE.

SPECIFICATION forming part of Letters Patent No. 694,038, dated February 25, 1902.

Application filed July 11, 1901. Serial No. 67,823. (No model.)

To all whom it may concern:

Be it known that I, WILLIAM E. STUBBS, a citizen of the United States, residing at the city of Chester, in the county of Delaware, 5 State of Pennsylvania, have invented certain new and useful Improvements in Puzzle Devices, of which the following is a full, clear, and exact description, reference being had to the accompanying drawings, of which—

10 Figure 1 is a plan view; Fig. 2, a section on line xx , Fig. 1, showing also one of the pins in a hole; Fig. 3, an enlarged elevation of a pin; Fig. 4, a diagrammatic plan showing a solution of the puzzle.

15 The nature of this invention is a puzzle device consisting of a block or board having a series of equidistant parts, such as holes therein, arranged in parallel equidistant rows and a cord or the like having secured thereto a series of parts, such as pins, a predetermined distance apart, the puzzle to be solved being to connect the parts consecutively of said cord with certain of the parts of the block in such manner that each of the 25 last-mentioned parts shall be engaged by or connected to one of said parts of the cord, respectively, as hereinafter described.

20 Referring to the accompanying drawings, 1 is a block of wood or other suitable material, which is provided with equidistant holes 30 2, occupying equidistant parallel rows arranged in the form of a square, as shown. 3 is a cord, to which are firmly secured equidistant pins 4, that are adapted to be entered into said holes. The distance apart of the pins is equal to the length of the diagonal line of a rectangle formed by six of said holes—that is to say, the distance, for example, between the corner hole marked *a* in 35 Figs. 1 and 4 and the hole marked *b*, as also the hole marked *c*.

40 In endeavoring to solve the puzzle the first pin upon the cord is thrust into one of the holes 2—as, for example, the corner hole *a*—45 the next pin into either the hole *b* or *c*, and so on, with the object of placing in like manner a pin in every hole of the series, each pin in succession being entered into a hole whose distance from such pin is equal to the distance from the latter to the next pin. To do 50 this is not easy, but may require many trials, for the reason that one is likely to soon ar-

rive at a point when the hole or holes in which the pin then in hand should be entered, or might have been, has been occupied by a preceding pin.

55 I have shown diagrammatically in Fig. 4 one solution of the puzzle, in this case the starting-point being at the hole *a* and the ending at hole *b*.

60 I prefer to make the pins of spring-wire bent into the form shown in Fig. 3—that is, with a head 4^a , that is clamped to the cord, and legs 4^b , bowed, as shown, and at their widest point of greater width than the diameter of the holes 2. Thus the pin may be readily entered into the latter, thereby forcing the legs toward each other, whereby it (the pin) is held sufficiently to prevent liability of being drawn out when the cord is manipulated in working out the puzzle.

65 Although in the particular illustration of my device shown in the drawings the block is provided with thirty-six holes, six rows of six holes each, occupying a square, there may 70 be a greater or less number arranged to form a square or rectangle. The greater the number of holes and corresponding pins on the cord the more difficult it will be to solve the puzzle.

75 I further remark that my device may be made in various forms without departing from the essential principle of the invention. For example, in lieu of the holes 2 and pins 4 there may be pins fastened to the board 1 80 and having projecting eyes secured to the cord, that are adapted to be engaged over the pins, the essential in this regard being that the block shall have parts or devices corresponding to the said holes and the cord, parts, 85 or devices corresponding to the pins.

90 In practice I would in order to keep together the block and cord permanently secure one end of the latter to the block at a proper point—as, for example, at or near the corner hole *a*.

95 Having thus described my invention, I claim as new and desire to secure by Letters Patent—

100 1. A puzzle device comprising a block having equidistant parts arranged in equidistant parallel rows, and a cord or the like, having parts corresponding in number to the said parts of the block, and whose distance apart

is equal to the length of a diagonal line of a rectangle formed by six or more of the parts of said block; the said parts of the cord being adapted to be engaged with and disengaged from the parts of the block, substantially as and for the purpose set forth.

2. A puzzle device consisting of the block having the series of equidistant holes therein arranged in equidistant parallel rows, and the cord, or the like, having the series of pins secured thereto whose distance apart is equal to the length of the diagonal line of a rectangle formed by six or more of said holes, substantially as set forth.

15 3. In a puzzle device of the character re-

cited, the combination of the block having the series of equidistant holes therein arranged in equidistant parallel rows, the cord, or the like, the series of equidistant pins secured thereto and having the bowed spring-shanks adapted to engage said holes, substantially as and for the purpose set forth. 20

In testimony whereof I have hereunto affixed my signature this 29th day of May, A. D. 1901.

WILLIAM E. STUBBS.
